SHUTTLE FOR NARROW WARE LOOMS

Application filed August 2, 1929. Serial No. 383,034.

This invention relates to improvements in shuttles for narrow ware looms and it is the general object of the invention to provide a shuttle with a compartment for carrying a 5 cop or large mass of wound weft.

In narrow ware shuttles commonly used the weft is wound on a quill which is rotatably supported on a pin and carried in the bow of the shuttle. In certain classes of work 10 it is desirable to employ a larger amount of weft than can be wound on a quill and it is an important object of my present invention to provide a shuttle having a preferably metallic yarn or cop carrying casing or shell 15 which is secured to a base similar to the supporting portions of the usual wooden narrow ware shuttles.

It is a further object of my present invention to provide a narrow ware shuttle having 20 a cop compartment defined in part by a cover pivoted to the casing and held in position by an improved form of readily detachable latch or hook.

With these and other objects in view which 25 will appear as the description proceeds, my invention resides in the combination and arrangement of parts hereinafter described and set forth in the claims.

In the accompanying drawing, wherein a 30 convenient embodiment of my invention is set forth,

Fig. 1 is a bottom plan of a narrow ware shuttle made according to my present invention,

Fig. 2 is a front elevation taken in the direction of arrow 2, Fig. 1,

Fig. 3 is a transverse section on line 3—3 of Fig. 2,

Fig. 4 is a detailed horizontal section on 40 line 4—4 of Fig. 2,

Fig. 5 is a perspective view of a portion of the metallic shell or casing,

Fig. 6 is a detailed vertical section on line 45 6—6 of Fig. 4, and

Fig. 7 is a detailed horizontal section on line 7—7 of Fig. 2.

It is to be understood that the loom in which my present form of shuttle is used will be provided with a lay having gear pinions rotatable preferably about horizontal

axes and meshing with a driving reciprocating rack extending the length of the lay. The loom will be arranged to weave a number of parallel webs spaced apart sufficiently to allow the shuttles to lie between the webs 55 when the lay is beating up.

In carrying my invention into effect I provide a shuttle with a base portion 10 which may be of wood or any other desired material, preferably non-metallic. This base is 60 provided with grooves 11 and 12 in the latter of which is formed a rack 13. The grooves cooperate with so-called shuttle blocks, not disclosed herein, to guide the shuttle as the same moves along the lay.

In the front portion of the base I provide a parti-cylindrical cavity 14 which extends 65 between holding and guiding arms 15 and 16 which project from the base 10 forwardly of the cavity, one from each end of the body. 70 Extending through the arm 15 is a weft receiving porcelain eye 17 communicating with the cavity and projecting beyond the forward extremity thereof.

A weft carrying shell or casing 20 is formed 75 preferably of sheet metal as set forth in Fig. 5 and has a rounded rear portion 21 which fits snugly into the cavity 14, being held therein by screws 22. The ends of the member 20 may be pointed as shown in Fig. 2 and 80 receive the correspondingly formed arms 15 and 16. The shell has the rounded portion thereof cut away at the ends as at 23 so that the forward portions of the arms 15 and 16 are not covered by the shell. The latter has 85 parallel spaced substantially horizontal walls 24 which together with the rounded portion 21 define three sides of a weft carrying compartment.

The other side of said compartment is 90 formed by a hinged cover 25 which is preferably concave with respect to the cavity 14 and is carried by a bearing member 26 mounted on a pin 27 extending between and secured to the parallel walls 24 adjacent that end of the shuttle carrying the eye 17.

In order to hold the hinged cap in position I provide a hook 28 pivoted on a pin 29 extending across the right end of the cavity 14 and secured to the body, as set forth in 100

Figs. 1 and 4. A screw 30 extends through an opening 31 in the hook and supports a washer 32 which covers the opening to limit movement of the hook in a clockwise direction as viewed in Fig. 4. The latter is urged to the left by a small compression spring 33 interposed between the arm 16 and the hook 28. The forward end of the hook extends through an aperture 34 formed in a holding element 35 riveted to the hinged cap 25.

The pivot pin 29, as disposed in Fig. 4, is so placed that the latch is diagonally disposed with respect to the cover 25, so that any outward strains of said cover will serve to tighten the grip which the latch has on the cover. This is due to the fact that the latch extends from its pivot in a direction away from the pivot of the cover and also away from the body.

20 Mounted on the hinged cover is a strap 36 having a threaded pin 37 on which is mounted one end of a tension spring 38. The latter is guided by pin 39 and bears against an inner friction disk 40, the outer disk 41 being secured to the strap. A delivery eye 42 is carried by the strap and the friction disks are located between said eye and the eye 17.

In operation, the hinged latch 28 will be moved to the right as viewed in Fig. 4 to permit the cover 25 to move to the dotted line position suggested in Fig. 1. The weft end of a cop is then threaded through the eye 17 and passed through a hole 43 formed in the strap, being then led between the disks 40 and 41 and out of the delivery eye 42. The cop is then pressed into the metallic casing between the walls 24, and the cover 25 restored to normal position, being held in place by the hook 28.

40 I find by using the metallic cap set forth herein that I can run the loom a greater length of time because of the fact that the cop carried in the casing holds considerably more yarn than can be wound on the ordinary quill. Furthermore, I find by making the shuttle partly of sheet metal and the base of the material of which shuttles are customarily made that my invention can be used in looms now in existence. Also, the latch is so arranged that it is prevented from loosening when a strain is brought to bear on the cover.

Having thus described my invention it will be seen that changes and modifications may be made therein by those skilled in the art without departing from the spirit and scope of the invention and I do not wish to be limited to the details herein disclosed, but what I claim is:

60 1. In a shuttle for narrow ware looms, a body having a cavity therein and having provision by which a shuttle may be moved, a metallic shell non-rotatably fixed to the shuttle at all times and having a portion lying within the cavity of the body, said shell being open on one side, and a cover pivoted

to the shell and movable pivotally through said open side and positioned to close the open side thereof to form a substantially closed metallic compartment for weft.

2. In a shuttle for narrow ware looms, a body having a cavity therein and having provision by which a shuttle may be moved, a metallic shell having a rounded portion lying within the cavity and having parallel spaced walls integral with the rounded portion, and a cover pivoted to the shell and movable between the walls to define with the latter and the rounded portion a substantially closed metallic weft carrying compartment.

3. In a shuttle for narrow ware looms, a body having a cavity therein and having provision by which a shuttle may be moved, a metallic shell having a rounded portion lying within the cavity and having parallel spaced walls integral with the rounded portion, a cover pivoted to the shell and movable between the walls to define with the latter and the rounded portion a substantially closed metallic weft carrying compartment, and means extending through the rounded portion into the body to hold said shell to the body.

4. In a shuttle for narrow ware looms, a body having a cavity therein and having provision by which a shuttle may be moved, the body having at each end thereof an extension, said extensions defining the length of the cavity, a metallic shell having portions lying between the extensions and in the cavity, and a cover pivoted to the shell and defining with the latter and the extensions a substantially closed weft carrying compartment.

5. In a shuttle for narrow ware looms, a body having a cavity therein and having provision by which a shuttle may be moved, the body having at each end thereof an extension, said extensions defining the length of the cavity, a metallic shell having portions lying between the extensions and in the cavity, and a cover pivoted to the shell and defining with the latter and the extensions a substantially closed weft carrying compartment, said shell having portions to extend around the extensions so that a portion of said shell is continuous around the periphery of the shuttle.

6. In a shuttle for narrow ware looms, a body having a cavity therein and having provision by which a shuttle may be moved, a metallic shell secured to the shuttle and having a portion lying within the cavity of the body, said shell being open on one side, a cover pivoted to the shell and positioned to close the open side thereof to form a substantially closed metallic compartment for weft, and a retaining latch pivoted to the shuttle and extending transversely of the

compartment and having holding engagement with the cover.

7. In a shuttle for narrow ware looms, a body having a cavity therein and having provision by which a shuttle may be moved, a metallic shell secured to the shuttle and having a portion lying within the cavity of the body, said shell being open on one side, a cover pivoted to the shell and positioned to close the open side thereof to form a substantially closed metallic compartment for weft, and a retaining latch pivoted to the body adjacent one end of the shuttle and extending transversely across the compartment in a direction away from the body and also away from the opposite end of the shuttle and having holding engagement with the cover.

8. In a narrow ware shuttle, a base having a cavity therein, a metallic shell fitting into the cavity, means to hold the shell in fixed position on the base at all times, a cover for the shell mounted thereon defining therewith a yarn carrying compartment, and means defining a pivotal connection between the shell and cover.

9. In a narrow ware shuttle, a base having a cavity therein, a metallic shell fitting into the cavity and having an opening on one side, means to hold the shell in fixed position at all times on the base, a cover for the shell to cover the opening and defining therewith a yarn carrying compartment, and a pivotal connection between the shell and cover so disposed that said cover is capable of movement through the said opening.

10. In a narrow ware shuttle, a base provided with a part to have engagement with a driving part of a loom, a metallic shell supported on and held fixed to the base at all times and having an opening therein to receive a mass of weft, a cover pivoted to the shell and movable to close the opening and form with the shell a weft chamber and a pivot for the cover extending in a direction transversely of the shuttle.

11. In a narrow ware shuttle, a base, a metallic shell held stationary at all times non-rotatably secured to the base and having an opening therein to receive a mass of weft, a pivot supported by and extending transversely of the shell, and a cover mounted on the pivot and movable to close the opening and form with the shell a weft chamber.

55 In testimony whereof I have hereunto affixed my signature.

ELBRIDGE R. HOLMES.
